UNITED STATES PATENT OFFICE.

VINTON E. SISSON, OF CHICAGO, ILLINOIS, ASSIGNOR TO WALTER P. MURPHY, OF CHICAGO, ILLINOIS.

CORRUGATED METAL END STRUCTURE FOR CARS.

Application filed October 1, 1920. Serial No. 414,058.

To all whom it may concern:

Be it known that I, VINTON E. SISSON, a citizen of the United States, residing at Chicago, in the county of Cook and State 5 of Illinois, have invented new and useful Improvements in Corrugated Metal End Structures for Cars, of which the following is a specification.

This invention relates to improvements in 10 end structures for railway cars and more particularly to sheet metal ends for freight cars.

The end of a freight car is subject to 15 very severe shocks and stresses on account of the tendency of the cargo to shift when the train starts and stops and in switching and also to the tendency of the superstructure of the car to weave while the train is in motion. To strengthen this type of car, 20 ends have been constructed of one or more sheets or panels of metal, usually steel, which sheets or panels are formed with corrugations for rigidifying the structure to more readily meet impacts from without, 25 cargo thrusts from within, and the racking strains from weaving.

It is the object of this invention to provide an end of the sheet metal type which is adaptable to either wooden car frames or 30 all metal freight cars and that may be employed for strengthening gondola cars, box cars, or other similar cars. It is a further object of this invention to provide the sheets or panels of the end with corrugations of 35 particular contour that from their form and length are peculiarly adapted to meet the stresses and strains already described. While the corrugations are preferably formed parallel, the relation to each other 40 or their direction is immaterial, likewise the corrugations may be all pressed from one side of the sheet of metal or may be formed from opposite sides, as desired.

While the preferred forms of this invention 45 are illustrated upon the accompanying sheets of drawings, yet it is to be understood that minor detail changes may be made without departing from the scope thereof.

In the drawings:

50 Figure 1 is a fragmentary view in end elevation of a box car illustrating an embodiment of this invention.

Figure 2 is a view in horizontal section 55 through the end taken on the line 2-2 of Figure 1.

Figure 3 is a view illustrating in diagram a cross section of a corrugated end plate or panel.

Figure 4 is a similar view showing the effect of a blow or impact upon such a 60 panel.

Figure 5 is a fragmentary view in front elevation of a corner of a panel illustrating a form of this invention.

Figure 6 is a sectional view taken on the 65 line 6-6 of Figure 5.

Figure 7 is a sectional view taken on the line 7-7 of Figure 5.

Figure 8 is an enlarged fragmentary view 70 in front elevation of a corner of a panel illustrating another form of this invention.

Figure 9 is a sectional view taken on the line 9-9 of Figure 8.

Figure 10 is a sectional view taken on the line 10-10 of Figure 8.

Figure 11 is an enlarged fragmentary view 75 in front elevation of a corner of a panel illustrating another form of this invention.

Figure 12 is a sectional view taken on 80 the line 12-12 of Figure 11.

Figure 13 is a sectional view taken on the line 13-13 of Figure 11.

An embodiment of this invention is illustrated as applied to a box car in which 85 the ends each comprise two or more sheet panels 1, preferably of pressed steel, which are attached to the corner posts, end plate and end sill in the usual manner. Figure 2 illustrates a means of attaching the panel 90 to a wooden corner post 2 by flanging the panel and securing the flange to the post.

In all forms shown, a plurality of strengthening corrugations having main walls 3 substantially flat and perpendicular 95 to the plane of the panel connected by portions 4 substantially flat and parallel to the plane of the panel, and of greater width than the height of the main walls, are formed in each panel, which corrugations 100 merge at their ends into the plane of the panel so that the panel has a flat marginal portion about its edges.

This general type of corrugation is shown 105 in diagram in Figure 3 in its normal position. When a panel of this form receives a blow of great force, such as an impact from shifting cargo, the panel will be bowed or bent outward in the direction of the blow on account of the resiliency or spring 110

like action of the bend in the metal between the main walls and connecting portions and if the blow is extremely severe causing an extreme bulging of the panel the 5 resiliency is not sufficient to return the panel to its normal plane leaving it bulged to a certain extent, defeating the object of the strengthened end.

It is an object of this invention to reinforce 10 the corrugations to resist such bending or bulging action of the panel so that the end will be sufficiently rigid to meet such exceptional impacts and remain in its normal plane. The resiliency of the panel is caused, as aforesaid, by the spring like action 15 of the bend of the metal where the main walls are joined by the connecting portions and also by the tendency of the metal in the connecting portions to spring or buckle at the same time. It is therefore desirable to rigidify the juncture of the main walls and connecting portions, or the surface of the connecting portions, or both, to carry out this invention.

Figures 5, 6 and 7 show a means for rigidifying the bend in the metal between the main walls 3 and the connecting portions 4 which comprises in providing a plurality of triangular rigidifying ribs pressed from the 30 main walls between connecting portions. The ribs are preferably arranged in equidistant pairs extending from opposite sides of the corrugations, and preferably comprise one series of ribs 5 pressed inwardly from the opposite main walls 3 and the alternating portions 4 connecting said walls, terminating at the juncture of the oppositely disposed connecting portions with said walls, and another series of similarly equidistant bosses 6 pressed outward from the 40 main walls 3 and the other alternating portions 4 connecting said walls, terminating at the juncture of the walls and first mentioned connecting portions 4, which alternate with the first series with each pair of one series lying midway between the adjacent pairs of the other series. The ribs 5 act as rigidifying ribs for the bend in the metal between the main walls and one series 50 of alternating connecting portions and the ribs 6 act as rigidifying ribs for the bends on the opposite sides of the main walls and their alternating connecting portions. These rigidifying ribs counteract the spring or 55 bending tendency of the juncture between main walls and connecting portions upon receiving a severe blow or impact and function to maintain the panel in its normal plane.

As aforesaid, there is also a tendency of the metal comprising the surface of the connecting portions between the main walls to give or buckle in the direction of the blow. Another means for rigidifying the end, in accordance with this invention, is to press

transverse elongated indentations or corrugations in the respective connecting portions 4, as shown in Figures 8, 9 and 10. It is preferable to press the indentations 7 in the series of alternating connecting portions 4, which lie in the same plane, inwardly between the main walls 3 connected thereby, as shown in Figure 9, and to press the indentations 8 in the opposite series of alternating connecting portions 4, which lie in the same plane substantially parallel to the plane of the first series, inwardly between the main walls connected by the latter portions 4, as shown in Figure 10. These indentations 7 and 8 are elongated and extend from the immediate proximity of one main wall to the immediate proximity of the other main wall connected by each portion 4 and are substantially parallel to each other and perpendicular to the main walls. It is preferable to arrange the indentations 7 of one series equidistant to each other and the indentations 8 of the other series similarly equidistant with the indentations of one series lying midway between the indentations of the other series, as shown in Figure 8. These indentations form strengthening or rigidifying ribs for the surfaces of the connecting portions 4 to resist any force which would normally bend or buckle the 90 surface in a direction at right angles to the length of the corrugations.

Figures 11, 12 and 13 show a panel 1 in which the bosses 5 and 6, shown in Figure 5, and the indentations 7 and 8 shown in Figure 8, are combined: In this form the pairs of bosses 5 and 6 and the indentations 7 and 8 are all equally spaced apart and so arranged that the center lines of the indentations 7 will pass through the bosses 6 and the center lines of the indentations 8 through the bosses 5. This latter form, shown in Figures 1 and 11, strengthens the panel against bulging by rigidifying the parts having a natural tendency to give or buckle and further strengthens the panel against all strains and stresses by disposing an equal amount of metal at a distance from the neutral axis of the panel in each corrugation.

A wooden lining 9 is preferably provided on the inner side of the end and a plurality of filler blocks 10 are received within and secured to a number of the corrugations to which the lining is attached. The filler blocks being beveled to pass between the bosses and transversely grooved to accommodate the transverse indentations.

Either series of ribs or either series of indentations may be used alone or any combination of ribs and indentations may be employed as may be desired without departing from the scope of this invention.

What I claim is:

1. A metal panel for car ends having a

plurality of reinforcing corrugations formed therein, said corrugations formed with wall members and wall connecting portions, and substantially triangular reinforcing ribs 5 connecting said wall members and wall connecting portions.

2. A metal panel for car ends having a plurality of reinforcing corrugations formed therein, said corrugations having wall members and wall connecting portions, said wall connecting portions having indentations formed therein. 10

3. A metal panel for car ends having a plurality of reinforcing corrugations formed 15 therein, said corrugations formed with main walls and connecting portions, and substantially triangular reinforcing ribs connecting said wall members and wall connecting portions, said wall connecting portions having 20 indentations formed therein.

4. A metal panel for car ends having a plurality of reinforcing corrugations formed therein, said corrugations formed with main walls and connecting portions between said 25 walls, said connecting portions having elongated indentations formed therein terminating within said connecting portion.

5. A metal panel for car ends having a plurality of corrugations therein formed 30 with main walls and alternating connecting portions between the opposite sides of the main walls, and ribs pressed in the main walls extending alternately into the respective alternating connecting portions adjacent thereto. 35

6. A metal panel for car ends having a plurality of corrugations therein formed

with main walls and alternating connecting portions between the opposite sides of the main walls, and ribs pressed in the main 40 walls extending alternately into the respective alternating connecting portions adjacent thereto, and indentations pressed in the said connecting portions.

7. A metal panel for car ends having a plurality of corrugations therein formed 45 with main walls and alternating connecting portions between the opposite sides of the main walls, and ribs pressed in the main walls extending alternately into the respective alternating connecting portions adjacent thereto, and transverse indentations 50 pressed in the said connecting portions with the bodies of said indentations entering between the said walls.

8. A metal panel for car ends having a plurality of corrugations therein formed with main walls and alternating connecting portions between the opposite sides of the main walls, and ribs pressed in the main walls extending alternately into the respective alternating connecting portions adjacent thereto, and transverse indentations in the connecting portions arranged in line with the ribs 55 extending from the adjacent main walls into the oppositely disposed connecting portions.

9. A metal panel for car ends having a plurality of reinforcing corrugations formed therein, said corrugations formed with main walls and connecting portions between said 60 walls, one of said connecting portions having elongated indentations formed therein terminating within said connecting portion. 70

VINTON E. SISSON.
